BASEBALL BAT

John E. Marsden, Philadelphia, Pa.

Application May 21, 1946, Serial No. 671,131

4 Claims. (Cl. 273—72)

1

This invention relates to baseball bats.

One object of the invention is to furnish an improved baseball bat having improved qualities in respect to strength, resilience, and lightness of weight.

It is well known that baseball bats are frequently broken, particularly when the bat strikes the ball in a direction at a certain angle to the grain thereof. It is a well settled practice that a baseball bat should be sufficiently large in diameter to afford an ample batting surface. As a result, it is difficult to keep down the weight of the bat, and a difference of only a few ounces may oftentimes have an important effect in the performance of a player, especially when he has to swing the bat with extreme rapidity against a high speed ball.

It is therefore an object of the invention to furnish an improvement in the art for overcoming these difficulties.

The cost of a good baseball bat is relatively high due to the special qualities of the wood employed and the seasoning thereof. Nevertheless, due to possible lack of uniformity in the wood, its resilience at different points about the circumference is somewhat uneven.

It is therefore another object of the invention to furnish a baseball bat of such improved construction that it can be made of relatively inexpensive materials, and may consist largely of rather cheap wood, nevertheless possess uniform resilience.

Another object of the invention is to furnish an improved bat whose grain is so arranged that breakage therealong is not possible in the manner in which it occurred heretofore.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a side view of a baseball bat embodying the invention.

Fig. 2 is an end view thereof.

Fig. 3 is a side view of one of a series of strip elements of which the bat is constructed.

Fig. 4 is a view of the cylindrical core of the bat.

2

Fig. 5 is an enlarged transverse cross sectional view of the bat applicable to any point along the length thereof.

Figs. 6, 7, and 8 are end views of different modifications of a baseball bat according to the invention.

The advantages of the invention as here outlined are best realized when all of its features and instrumentalities are combined, but useful embodiments may be produced involving less than the whole.

It will be obvious to those skilled in the art to which the invention appertains, that the same may be incorporated in several different constructions. The accompanying drawing therefore, is submitted merely as showing a preferred exemplification of the invention.

Referring in detail to the drawing 10 denotes a baseball bat embodying the invention. The same comprises the usual batting portion 11, handle portion 12, and enlargement 13, which portions are in perfectly aligned and true relation with each other, and provide a streamlined configuration. The bat 10 includes a cylindrical core or rod 14 about which is disposed a series of radial segments 15. While the rod 14 is preferably of uniform diameter throughout, the segment 15 varies in dimension to conform to the outer contour of the bat 10. Thus the segment 15 has an inner edge 16 which in this instance may be straight throughout to seat against the surface of the core 14, and an outer edge or surface 17 which is curved at 18 and 19 to correspond to the portions 11, 12, and 13. Because of the circular cross section of the bat 10, all of the segments 15 are of wedge shaped form, as clearly shown in Fig. 2. For simplicity in manufacture, the wedge angle is preferably uniform throughout the length of the segment 15. Accordingly all of the portions 11, 12, and 13 consist of segments which are principally wedge shaped. Best results are obtained by making elements 14 and 15 of a length equal to the overall length of the bat. It will thus be clear that the cross sectional view of Fig. 5 is applicable to any point along the bat.

The core 14 and the series of segments such as 15 are secured in assembly relation with each other to produce the bat 10 in any suitable manner. Any desired fastening means may be employed for this purpose. The best results are obtained by bonding or adhesively uniting the various elements, preferably throughout their contacting surfaces. Thus an adhesive may be used such as a glue or plastic material. The

adhesive joints between elements 15 are at 15b, and the joints between these elements and the core are at 15c. The water soluble glue has been found satisfactory. It is preferred that the adhesive agent shall not so penetrate the material of which the elements are made as to impart undue stiffness thereto and render them brittle and liable to breakage.

According to Fig. 5, it will be noted that the segments 15 are constructed of wood whose grain is so arranged as shown at 15a, that in the transverse direction it extends in general parallelism with the individual elements 15. In other words, in the assembled bat 10, the grain is approximately radial at all points throughout the circumference of the bat throughout the length thereof. The strips or segments 15 are made of wood sufficiently uniform in grain for this purpose, and are cut in such a manner as to achieve this result. The grain of the core 14 is relatively immaterial, and it suffices that it be formed of a strong and tough wood to serve as an axial bracing or stiffening element of highly uniform resilience. Another advantage in the use of the core 14 is that it affords a good seat or bearing for the segments at 16. In other words, if the core was not used, it might be necessary to cut the segments 15 substantially to a feather edge at 16. This would increase the cost of manufacture, and would tend to diminish the strength of the bat. In certain cases, the space occupied by the core 14 may be left open or may be filled with a plastic hardening material. If desired, a hollow, metallic tube may be substituted for the core 14.

In manufacture, it is merely necessary to provide a series of identical segments 15 and a rod such as 14, the contact surfaces of all of which are wetted with a suitable adhesive or glue which need be applied only sufficiently to secure good adhesion between the parts. The assembly is then placed in a suitable die, and the adhesive permitted to dry or otherwise harden under pressure applied by the die, and with the application of a suitable degree of heat if necessary. Finally the outside surface of the bat may be cut down slightly if necessary, to achieve a perfectly smooth surface. The bat is now complete and of course it may be varnished or stained if desired.

The bat 10 will not break or split along the grain because the impact of the ball is always against the grain, and the segments 15 are sufficiently narrow to tend to interrupt a breaking strain, this effect being probably assisted by the adhesive at the joints of the parts. In effect, the adhesive may be stronger than the wood itself, but because it is used in a rather limited amount, resilience is preserved without producing brittleness. In fact, there may be a shock absorber quality at the seams due to the use of different materials, the properties of the adhesive being different than those of the wood. Because of the radial segments, the resilience will be uniform around the circumference of the bat. The latter may be constructed of relatively inexpensive wood, or of scraps thereof, and satisfactory results have been obtained with white pine. The woods employed may be relatively light in weight, and thus a bat may be constructed whose batting portion 11 may have the requisite diameter to afford a large batting surface without unduly increasing the weight of the bat. It is thus possible for the manufacturer, by proper selection of woods, to produce bats of different weights and large diameter while maintaining the strength and

resilience of the bat, and such bats may be comparatively inexpensive.

In Fig. 6 is shown a modification 20 which is in all respects like the bat 10 except that it illustrates that certain of the segments need not be angular or wedge shaped, and it further shows that a single strip of material may be used passing right through the bat along a diameter thereof. Thus there is shown a strip element 21 which may be of generally uniform width, except that it may include an integral core portion 22 which may be defined by the grooves 23, or by making the core portion larger in diameter than the thickness of the strip, or both. Certain segments 24 may be shaped at 25 to conform to the grooves 23, while the other segments 26 may be wholly uniform like those at 15. All of the segments 24 and 26 may seat against the core portion. The same structure may be maintained at every point in the cross section throughout the length of the bat 20.

In Fig. 7 is shown a modified bat 30 which is intended to illustrate a structure whereby a core may be omitted without employing an unduly sharp feather edge at the axis of the bat. The latter may comprise a series of wedgelike elements whose angle is increased at 32 to furnish a longitudinal lip or flange, whereby the several elements 31 are formed with relatively blunt nose portions with the different elements directly angularly abutting each other in a complete circle. Between the different elements 31 are disposed the complementary segments 33 whose inner edges sit on the portions 32, the latter thus acting as a sectional core for the elements 33. In other respects the bat 30 is like that at 10.

In Fig. 8 is shown a bat 35 which is like that shown at 10, except that it illustrates the breaking of radial joints between the segments such as 15 in the bat 10. In the instant bat there is a core 36 formed separately or integrally with one or more of the segments in a manner illustrated in Figs. 6 and 7, and cooperating therewith is a series of segments 37 whose inner portions 38 may be of increased width to form a shape like a keystone. These portions 38 form the seams 39 terminating at the shoulders 40. Seated upon the latter and between the elements 37 are the segments 41, 42 which may be of like or varying widths, thus producing seams 43 staggered or offset with respect to the seams 39. By this construction the strength of the bat may be substantially increased, and all the other advantages thereof maintained.

As used herein, the term "segment" may apply to a strip element generally radial to the bat and being of either uniform thickness or wedge shaped form. It will be appreciated that any suitable number of such segments may be employed, satisfactory results having been produced by using between 12 and 16 segments of the type shown at 15.

I claim:

1. As a new article of manufacture, a baseball bat having an axially extending core, a circular series of longitudinal wooden segments with the grain of the wood being generally radial throughout, each of said segments having an inner portion keystone shaped in cross-section in contact with the core and an outer portion of reduced width extending radially of said keystone portion to form shoulders, a plurality of wedge shaped segments each interposed between consecutive said outer portions and seated upon said shoulders,

said core and all of said segments being adhesively united together.

2. As a new article of manufacture, a baseball bat having an axially extending core, a plurality of longitudinal wooden segments with the grain of the wood being generally radial throughout arranged in a circular series about said core with their inner portion in abutting relation with adjacent segments and with the core, each segment having an outer portion of reduced width extending radially to the outer surface of the bat, and other wedge shaped segments inserted, one on each side of said outer portion, said core and all of said segments being adhesively united together.

3. As a new article of manufacture, a baseball bat having a circular series of longitudinal wooden segments substantially wedge shaped in cross-section with the grain of the wood being generally radial throughout, said series comprising a set of alternate segments extending radially from the axis to the outer surface of the bat and having an apex angle, each of said alternate segments abutting adjacent alternate segments in the apex angle region to form an axial core, and a second set of segments each alternately interfitted between two of said first alternate segments and extending radially from a point spaced outwardly from the axis to the outer surface of the bat, all of said segments being adhesively united together.

4. As a new article of manufacture, a baseball bat having a circular series of longitudinal wooden segments with the grain of the wood being generally radial throughout, the segments having bonding seams therebetween extending substantially radially, a substantial number of the seams having portions extending at an angle to said radial direction at a point between the axis of the bat and the outer surface thereof, adjoining segments having cut away portions to the outer surface, and wedge shaped segments inserted in said cut away portions.
